CARDBOARD CARTON

Donald F. Cunningham, Milwaukee, Wis., assignor
to Pabst Brewing Company, Chicago, Ill.

Application May 30, 1942, Serial No. 445,151

4 Claims. (Cl. 229—52)

This invention appertains to a combined carton and carrier for bottles and is an improvement on the structure shown in the Darragh and Rue application Serial #438,054 filed April 8, 1942.

In the mentioned pending application it was necessary to bend or flex the end flaps to insert them inside the outer case for interlocking engagement with the inner bottle partition or filter, when assembling the carton.

One of the primary objects of my invention is to form the end flaps in such a manner that the same can be readily swung into the case for cooperation with the filler without the necessity of bending or flexing the end flaps.

Another salient object of my invention is to provide novel means for automatically and detachably locking the end flaps to the body of the case when said end flaps are swung inside of the case, whereby all danger of the end flaps being dislodged from their normal operative position is eliminated.

With these and other objects in view the invention consists in the novel construction, arrangement and formation of parts, as will be hereinafter more specifically described, claimed and illustrated in the accompanying drawing in which drawing:

Figure 1 is a vertical longitudinal sectional view through my complete carton, showing one of the end flaps in its normal operative position and the other flap being swung to its lower normal operative position, the section being taken on the line 1—1 of Figure 4 looking in the direction of the arrows.

Figure 2 is a view similar to Figure 1 but showing a part of the inner filler moved to its raised operative position for facilitating the carrying of the carton.

Figure 3 is a transverse sectional view through the carton taken on the line 3—3 of Figure 2 looking in the direction of the arrows.

Figure 4 is a horizontal sectional view taken on the line 4—4 of Figure 2 looking in the direction of the arrows.

Figure 5 is a plan view illustrating the blank from which the outer case is formed.

Referring to the drawing in detail, wherein similar reference characters designate corresponding parts through the several views, the letter "C" generally indicates the novel carton, and the same includes an outer case or container 10 and an inner bottle partition filler or insert 25.

The case or container 15 can be formed from 55 provided with an inwardly directed central slot

cardboard or other preferable material and of a size to conveniently hold six bottles of beverage, but obviously the complete device can be formed in different sizes not only for the purpose of receiving different sizes and shapes of bottles but also for the purpose of receiving any desired number of bottles. Likewise both the outer case 10 and the bottle partition filler or insert 25 are preferably of such a construction that the entire device can be shipped in a knockdown or flat condition, and then readily assembled at the point of use.

The outer case 10 is formed from a single blank of sheet material and this blank is shown in detail in Figure 5 and the case includes end walls 11 and 12, and side walls 13 and 14. The end wall 12 can have formed one longitudinal edge a sealing lip 15, which can be securely fastened to the side wall 14 by a suitable adhesive or clips to form the body of the case.

The bottom wall of the case is constructed in the same manner as in the pending application mentioned and briefly the lower edges of the side and end walls carry flaps which are folded to 25 form the bottom wall and these flaps will not be described in detail.

The upper edges of the end walls 11 and 12 have formed thereon top end wall flaps 16. These flaps 16 are of a novel construction and form an important part of the present invention and will be later described in detail. The side walls 13 and 14 have formed thereon the side top wall closure flaps 17 and when the carton is assembled these top side wall flaps are folded down over the tops of the bottles.

Also in accordance with the present invention, the blank has cut therein at the point of juncture of the walls 12, 13, 11 and 14 and at the point of juncture of the sealing lip 15 with the wall 12, U shaped slits 18. Hence these U shaped slits 18 are at the corners of the case and when the case is folded, the material defined by the slits will swing out of the slits and form slots 19, the purpose of which will also be later set forth.

It is to be noted, however, that the slots 19 are disposed adjacent to the upper end of the case. Again referring to the blank, it will be noted that the outer longitudinal edge of the side wall 14 is provided with a notch 20 which is in longitudinal alignment with the slits 18 and this notch is formed so that when the blank is folded, to form the case, the adjacent slot 19 will not be closed by said side wall.

The top end flaps 16 are each bifurcated or

21 and the walls of each slot 21 gradually curve outwardly toward the outer ends of the flaps 16 to provide a flaring guide entrance mouth 22. The side edges of the end flaps are provided with outwardly extending locking tongues 23 and it will be noted that these tongues 23 have a width equal to the length of the slots 19 and are disposed the same distance away from the upper edge of the walls of the case as are the slots 19. These tongues 23 can be struck out from adjacent portions of the blank. (See Figure 5.)

The insert or bottle partition filler 25 is substantially of the same construction as the mentioned pending application and hence this filler will not be described in great detail, but it is to be noted that the same includes a main sliding body section 26 and a lower auxiliary section 27. The main body section includes abutting companion side walls 28 joined at their upper ends, and the side edges of these abutting side walls have formed thereon laterally extending wings 29. These wings slidably engage the inner face of the end walls 11 and 12 of the case. Attention is called to the fact that the outer edges of the wings 28 at the upper ends are tapered as at 30 for clearing the locking tongues 23 on the end flaps 16 when the end flaps are swung into the case as will be later described. The upper end of the sliding main body section 26 of the insert or filler is shaped to form a hand grip or handle and consequently the abutting walls 28 are provided with registering slots 31 and the side edges of these abutting walls are inclined or curved downwardly to define the handle and to form guide surfaces, the purpose of which will later appear.

At the bottling plant the cases 10 are folded and set up and the inserts 25 are assembled and placed in the cases. The end flaps 16 are now swung down inside of each case and it is to be noted that the slots 21 are in longitudinal alignment with the handle of the filler and these slots are of such a depth as to clear the handle or if preferred the inner walls of the slots can ride on the inclined or curved outer edges of the handle. But in all events, the slots 21 permit the swinging of the end flaps 16 into the case without bending or flexing. The end flaps 16 are swung into the case and over the wings 29 of the insert or filler until the locking tongues 23 snap into the slots 19, which effectively hold the end flaps in their folded condition against movement. These end flaps 16, then define, in conjunction with the end walls 11 and 12, guide ways or tracks for the wings 29 on the insert.

The cases can now be conveniently filled with the bottles from a bottle loading machine, as it can be seen that the tops of the cases are entirely clear of all obstructions.

When a customer purchases a carton of bottles, the handle portion of the insert is grasped and pulled upwardly. This slides the main portion of the insert within the case, and the handle portion will be disposed exteriorly of the case whereby the container can be conveniently carried by the purchaser.

When the main portion 26 of the insert is slid upwardly, the upper edges of the wings 29 will strike the score lines for the end flaps 16 and the upper edges of the wings will rest against the case at the point of juncture of the flaps with the end walls 11 and 12. Thus further upward movement of the insert is prevented. As stated, dislodgment of the end flaps 16 is prevented due

to the fact that they are securely locked in place with the body of the case.

From the foregoing description it can be seen that the construction of the carton shown in the pending application has been improved and that the end flaps of the case can be conveniently and quickly swung into the body of the case without bending or flexing and thereafter firmly latched to the case.

Changes in details may be made without departing from the spirit or scope of my invention, but what I claim as new is:

1. A combined bottle carrier and carton comprising an outer case, a bottle partition filler fitted in said case including a sliding central partition wall and laterally extending wings on the ends of said partition wall, said wings having a sliding engagement with the end walls of the case, said case also including swinging cover flaps moveable inside of the case parallel with the wings and the end walls of the case and into engagement with the wings for retaining the filler in place, the cover flaps each being provided with a central slot for clearing the partition during the swinging of the flaps into the case, the case having keeper slots therein, and laterally extending locking tongues on the sides of the flaps moveable into the keeper slots when the flaps are swung into engagement with the wings, the flaps defining in conjunction with the end walls of the case a slide guide way for said wings.

2. A combined bottle carrier and carton comprising an outer case, a bottle partition filler fitted in said case including a sliding central partition wall and laterally extending wings on the ends of said partition wall, said wings having a sliding engagement with the end walls of the case, said case also including swinging cover flaps moveable inside of the case parallel with the wings and the end walls of the case and into engagement with the wings for retaining the filler in place, the cover flaps each being provided with a central slot for clearing the partition during the swinging of the flaps into the case, the case having keeper slots therein, and laterally extending locking tongues on the sides of the flaps moveable into the keeper slots when the flaps are swung into engagement with the wings, the flaps defining in conjunction with the end walls of the case a slide guide way for said wings, the walls of the slots in said flaps being inclined outwardly to form wide flaring guide mouths.

3. A combined bottle carrier and carton comprising an outer case, a bottle partition filler fitted in said case including a sliding central partition wall and laterally extending wings on the ends of said partition wall, said wings having a sliding engagement with the end walls of the case, said case also including swinging cover flaps moveable inside of the case parallel with the wings and the end walls of the case and into engagement with the wings for holding the filler in place, the cover flaps each being provided with a central slot for clearing the partition during the swinging of the flaps into the case, the case having keeper slots therein, and laterally extending locking tongues on the sides of the flaps moveable into the keeper slots when the flaps are swung into engagement with the wings, the flaps defining in conjunction with the end walls of the case a slide guide way for said wings, the walls of the slots in said flaps being inclined outwardly to form flaring guide mouths, the ends of said wings at their upper portions being tapered whereby to clear said locking tongues

upon upward sliding movement of the central partition.

4. A combined bottle carrier and carton comprising an outer case having side and end walls, a removable bottle partition filler slidably fitted in said case including a central partition extending from one end of the case to the other having laterally extending wings on each end thereof, the wings slidably engaging the end walls of the case, said case also including end cover flaps formed on the end walls movable inside of the case over and into engagement with said

wings and parallel with said wings and said end walls defining in conjunction with said end walls slideways for the wings, said end cover flaps having slots for clearing said central partition, whereby said flaps can be swung into position and into engagement with said wings without bending, and means detachably locking the flaps to the side walls of the body in their parallel position with the wings against swinging movement.

DONALD F. CUNNINGHAM.
